UNITED STATES PATENT OFFICE.

BERNARD M. O'BOYLAN AND JOHN THOMPSON, OF CORNING, OHIO.

NECK-YOKE.

SPECIFICATION forming part of Letters Patent No. 443,374, dated December 23, 1890.

Application filed July 1, 1890. Serial No. 357,403. (No model.)

To all whom it may concern:

Be it known that we, BERNARD M. O'BOYLAN and JOHN THOMPSON, citizens of the United States, residing at Corning, in the county of 5 Perry and State of Ohio, have invented new and useful Improvements in Neck-Yokes, of which the following is a specification.

Our invention relates to neck-yokes, and has for its object to produce simple, durable, 10 and inexpensive anti-friction attachments for connecting the neck-yoke bar with the hames and with the pole of a carriage or other vehicle.

The invention consists in the construction 15 and combination of parts hereinafter described and claimed.

In the annexed drawings, illustrating the invention, Figure 1 is a view of a carriage neck - yoke embodying our improvements. 20 Figs. 2 and 3 are detail views.

Referring to the drawings, the numeral 1 designates a neck-yoke bar of the usual construction.

On the center of the neck-yoke bar 1 is 25 freely supported a movable collar 2, which may be made of leather or metal, as preferred. The collar 2 supports a pole-holder 3, which may also be made either of metal or leather. The pole-holder 3 is attached to the collar 2 30 by a swivel or pivotal connection 4, and has an eye 5 for engaging the carriage-pole. A staple 6, inserted in the neck-yoke bar 1 and loosely embracing the collar 2, serves to limit the longitudinal movement of said bar and collar with relation to each other.

On each end of the neck-yoke bar 1 is freely 35 supported a metal or leather collar 7, which is held on the bar by a staple 8, that loosely embraces the collar in such a way as not to interfere with its necessary movements. The 40 collars 7 each support a strap-attaching clip 9, that may be made of leather or metal. This clip 9 is attached to the collar 7 by a swivel or pivotal connection 10, and is provided on its opposite sides with coincident 45 slots 11 for engagement of a strap 12, that connects with the hames. Each clip 9 preferably consists of a strap of leather or metal doubled at its center, near which point it is 50 provided with the slits 11, and having its ends connected with the collar, as shown.

It will be seen that the collars and attached clips or holders are so constructed and arranged that each collar and connected clip or holder constitute a universal anti-friction attachment that will save wear and expense wherever used, either as a neck-yoke attachment or in other parts of a harness or elsewhere, as desired. When the collars are made of leather, they may be provided with a 60 lining of rolled metal to prevent the leather from stretching. By means of these attachments the wear of the neck-yoke bar and breast-straps is greatly diminished by reason of the movable collars 2 and 7 being freely 65 supported on the neck-yoke bar and arranged to have a swiveled or pivotal connection with the attached strip-clips and the pole-holder, as described. The operation of these attachments and their utility in greatly diminishing 70 wear and friction will be readily understood.

The devices are simple and inexpensive and can be readily applied to the uses for which they are adapted and designed. 75

What we claim as our invention is—

1. The combination, with the neck-yoke bar, of the movable collars freely supported on the ends of said bar and the slotted clips having a pivoted connection with said collars, substantially as described. 80

2. The combination, with the movable collars, of the doubled clip pivotally connected with said collars and provided with the slots for engaging a strap, substantially as described. 85

3. The combination of the neck-yoke bar provided with staples at its center and ends, the movable collars surrounding said bar within the staples, and the clips or holders having a pivotal connection with the said collars, substantially as described. 90

In testimony whereof we have affixed our signatures in presence of two witnesses.

BERNARD M. O'BOYLAN.
JOHN THOMPSON.
